(57) **CLAIM**

The ornamental design for a CD player storage bag, as shown and described.

DESCRIPTION

FIG. 1 is a top perspective view of a CD player storage bag, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view showing the CD player storage bag in an open state thereof; and,

FIG. 10 is a rear perspective view showing the CD player storage bag in an open state.

The broken lines in the drawings illustrate the portions of the CD player storage bag, which form no part of the claimed design.

1 Claim, 10 Drawing Sheets
